UNITED STATES PATENT OFFICE.

JAMES OSBORN BERRY, OF BELLEVUE, TEXAS.

WIRE-FENCE TOOL.

SPECIFICATION forming part of Letters Patent No. 692,818, dated February 11, 1902.

Application filed July 8, 1901. Serial No. 67,564. (No model.)

To all whom it may concern:

Be it known that I, JAMES OSBORN BERRY, a citizen of the United States, residing at Bellevue, in the county of Clay and State of Texas, 5 have invented a new and useful Wire-Fence Tool, of which the following is a specification.

The invention relates to improvements in wire-fence tools.

The object of the present invention is to 10 provide a simple and comparatively inexpensive tool of great strength and durability designed for operating on fence-wires and adapted for mending the same and for taking up the slack of a fence-wire and capable in stretching the ends of a broken or severed wire of drawing the said ends past each other before the same are twisted together, whereby the ends of the wire may be more effectively connected.

20 The invention consists in the construction and novel combination and arrangement of parts hereinafter fully described, illustrated in the accompanying drawings, and pointed out in the claim hereto appended.

25 In the drawings, Figure 1 is a perspective view of a tool constructed in accordance with this invention, the jaws being separated preparatory to stretching a fence-wire. Fig. 2 is a side elevation illustrating the position of 30 the jaws after the wire has been stretched and the ends thereof drawn past each other. Fig. 3 is a detail view of the jaws of the bars or members, illustrating the arrangement of the same.

35 Like numerals of reference designate corresponding parts in all the figures of the drawings.

1 and 2 designate two bars or members pivotally connected between their ends by a rivet 40 3 or other suitable fastening device, and provided at their inner ends with laterally-extending handles or grips 4, and having jaws 5 at their outer ends. The bars or members 45 may be constructed of any suitable metal, and their jaws 5, which are curved, are deflected or offset laterally from each other in order that they may clear and swing entirely past each other during the operation of stretching a fence-wire, as hereinafter explained. The curved jaws, which are enlarged, are provided with V-shaped recesses 6 to form claws for engaging the ends of a

broken or severed fence-wire, as illustrated in Fig. 1 of the accompanying drawings, and after the ends of the fence-wire have been secured to the jaws in this manner the wire is stretched by bringing the handle portions of the jaws together and swinging them past each other to carry the jaws from the position shown in Fig. 1 to a position similar to 60 that illustrated in Fig. 2. The pivoted bars or members are adapted to be entirely rotated in opposite directions on their pivot, and by swinging the jaws past each other in this manner the wire may be stretched to a greater degree than is possible with jaws or members which are adapted to swing substantially to a closed position only, and the ends of the wire may be drawn past each other and overlapped before they are twisted. By this construction a more effective knot is produced. The tool may be used in this manner for connecting the ends of a broken fence-wire, or it may be employed as a mid-wire take-up, in which case the wire is preferably severed and 75 then stretched to the desired tension. The laterally-extending handles 4 project outward a considerable distance and form a lever for enabling the wire to be easily twisted after the same has been stretched, as before described. These laterally-extending handles may be formed by bending the inner ends of the bars or members outward, or they may be constructed in any other suitable manner.

The bar or member 1 is provided beyond 85 the pivot 3 with a wire-receiving notch 7, and the bars or members are adapted to be closed on the wire to sever the same, and an efficient wire-cutter is thus provided. The device is also adapted to be used as a gage for enabling 90 the wires to be spaced at equal intervals, the device being adapted to be hung on a wire by means of the laterally-extending handles, and the bars or members by depending from such wire will serve as a gage. In constructing the tool the bars or members may be made of different lengths, as will be readily understood.

It will be seen that the tool is exceedingly simple and inexpensive in construction, that it possesses great strength and durability, and that it is adapted for stretching and repairing fence-wires. It will also be apparent that the tool is adapted to stretch the ends of a

fence-wire past each other and that an effective knot or connection may be readily produced.

What I claim is—

- 5 A tool for stretching and repairing fence-wires comprising two bars 1 and 2 pivoted together between their ends and having their outer ends enlarged and provided with laterally-offset claws arranged to clear each other
10 entirely and adapted to engage the ends of a broken fence-wire and capable of swinging entirely past each other, whereby the ends of the wire may be stretched to the desired tension prior to twisting them together, said

bars being provided at their inner ends with 15 laterally-projecting handles arranged at right angles to the bars and extending outward at right angles to the line of movement of the bars and adapted to be readily grasped while stretching a fence-wire, substantially as described. 20

In testimony that I claim the foregoing as my own I have hereto affixed my signature in the presence of two witnesses.

JAMES OSBORN BERRY.
